VACUUM BREAKER

James G. Cekal, Chicago, Ill., assignor to Crane
Co., Chicago, Ill., a corporation of Illinois

Application May 18, 1935, Serial No. 22,187

15 Claims.

(Cl. 4—70)

More particularly, my invention relates to an improvement in such devices known to those skilled in the art as vacuum breakers and is preferably used in combination for flushing such fixtures as for example, water closet bowls, urinals and the like.

Among the more important objects of this invention is to absolutely prevent any possibility of reverse flow into the fresh water supply system as might ordinarily be created by a vacuum in the latter.

Another important object is to provide a device that absolutely insures proper resealing of closet bowls and similarly constructed or sealed fixtures.

Another important object is to provide for a construction which is relatively simple and inexpensive to manufacture, and yet is suitable for installation under present piping conditions.

It is well accepted that prior devices of this general character have been used for this purpose, but none of these heretofore available, to my knowledge, has been successful where relatively high flushing pressures are employed.

In contradistinction, through the application of a principle involving the use of an ejector, an outlet orifice arrangement, and a system of effective baffles, I have overcome the objectionably insanitary flooding and spilling or backing up within the vacuum breaking device on high pressures and I have thus expedited its efficient operation over a wide range of pressures.

More specifically, I have found that by a careful mechanical selection and arrangement of baffles, what is commonly termed "spitting" or throwing droplets of flushing water into the atmosphere through the air ports or vents can be prevented to a certainty, and at the same time allow for the use of a very generous air-way communication between the nozzle of the device and the exterior surrounding atmosphere.

Thus it is another important object to reduce to a minimum the possible lift of water within the outlet tailpiece of the device under high vacuum conditions, with the obvious advantage of permitting the lower portion of the vacuum breaker to be set relatively close to the water closet rim top. The latter advantage is of course particularly valuable when considering existing installations where space to accommodate the vacuum breaker device is frequently limited.

This invention has other objects which will become apparent upon proceeding with the following description and as disclosed by the drawing.

55 Referring to the drawing:—

Fig. 1 is a sectional assembly view of a preferred embodiment, the said section being taken in a central longitudinal position.

Fig. 2 is a cross-sectional view of the aforesaid construction taken on the line 2—2 of Fig. 1.

Fig. 3 is an exterior front view with a section partially broken away and showing a modified construction of my invention.

Fig. 4 is a fragmentary sectional view of a modified form of an outlet ring for use under special conditions.

Like numerals refer to like parts throughout the several figures.

Referring now to the drawing and specifically to Fig. 1, the cap or head 1 by means of the threads 2, or by any other conventional means of attachment, as for example, soldered or brazed joints, is connected usually to an inlet supply pipe (not shown) leading from such liquid control device, as for example, a flushing valve (also not shown) which thereby regulates the flow of the flushing water into the inlet passage 3 and through the throat 4 of the nozzle member 4b. The latter member may be separate and threadedly or otherwise attached to the head 1, as indicated, or else may be made integrally as a part of the member 1.

Similarly, the head 1 may be threadedly or otherwise attached to the body or casing 5 by means of the screw threads 6 and between which latter connection is interposed the inner rim of the shield or hood 7, the purpose of which will hereinafter be referred to in greater detail.

Before the head 1 and the body 5 are assembled, as indicated, however, the outlet ring 8 is preferably threadedly or otherwise attached as at 9 to the outlet or discharge portion of the body 5. The outlet ring 8 is provided with an inwardly extending flanged portion 12 which serves the purpose of properly restricting the orifice 13 so as to provide a shoulder or secondary baffle 14 which will tend during the flushing operation to prevent the back-flow of the line flushing water from the tubing 11 back or upward into the interior or periphery of the body 5, after having previously passed the orifice 13. A leak-proof joint is preferably formed as at 15 to prevent any line leakage past the joint into the exterior atmosphere.

The primary baffle 16 which is preferably of an inverted frusto-conical form, having a lower central port 16a, is provided with the upwardly extending prongs 17 frictionally engaging the interior peripheral surface 18 of the body 5 and rests upon the lugs 19 within the latter member. It is thus apparent that by a proper spacing of 55

- the aforesaid prongs 17 and also in providing that the larger diameter of the frusto-conical baffle is less than that of the interior peripheral surface 18 of the body 5, an annular space 18a is accordingly formed. The lower portion of the baffle 16 is so positioned with respect to the sloping annular surface 18a of the outlet ring 8 that an annular space 18c is thus formed, the purpose of which will be later described.
- 10 The baffle 16 is held in position and restrained against any upward movement due to possible reversal of flow or back pressure preferably by the ends of the said prongs abutting against the underside of the shoulder 21 of the baffle ring 22.
- 15 The latter ring is preferably attached as at 23 to the casing 5, forming a leak-proof contact as at 24 by means of the shoulder. The lower end 22a of the baffle ring 22 is likewise positioned with respect to the upper portion of baffle 16 to form an annular space 18b. It is thus obvious that there is communication between the space 18c and the space above the upper sloping surface 16b of the baffle 16 via the annular openings 18a and 18b.
- 20 A cylindrically formed ring 25 by means of the prongs 26 engages the annular recess 27 of the baffle ring 22, and likewise is fixedly held against upward movement by means of the prongs 26 engaging the shoulder 28, the purpose of the ring 25 being to serve as a spray baffle tending to restrain or limit the possible escape of the flushing water droplets to atmosphere, and may, depending upon the installation pressure condition encountered, be dispensed with.
- 25 The upper portion of the body 5 is provided with the air vents 5a formed by the equally spaced and preferably integral ribs 5b on the body 5 and preferably positioned diametrically opposite for purpose of support of the upper annularly threaded portion 6, although of course, it is obvious that the size and the number of the ribs 5b and the vents 5a may be varied according to the manufacturer's discretion for best results and operation.
- 30 The throat 4 is preferably made of sufficient length so as to allow the stream emerging at the mouth 4c of the nozzle member 4b to flow through the port 16a of the baffle 16 without any tendency to splash or spread upon the inclined surface 16b of the baffle 16. On relatively high pressures, the flushing stream emerging from the mouth 4c of the nozzle member 4b acquires an increased velocity and thereby tends to expand gradually at a distance somewhat below the port 16a. Accordingly, the diameter of the flushing stream likewise is slightly greater at approximately the point where it enters the orifice 13. As a result a slight radial flow outwardly commences describing a path by way of the previously referred to annular spaces 18c, 18a and 18b in the order mentioned and subsequently being diverted into the space above the sloping surface 16b of the baffle 16, by reason of the lip 22a of the baffle ring 22. However, the flushing stream moving at a relatively high velocity through the port 16a of the baffle 16 creates a combined inspiratory ejector action by drawing in air through the vents 5a and also any liquid that might tend to flow from the annular opening 18b. The ports 5a are directly connected to the atmosphere by reason of the downwardly extending peripheral wall of the hood 7 which serves to guard against the likelihood of foreign matter entering therewithin.
- 35 Referring now to the modification shown in

Fig. 3, in this instance the nozzle member 4b is provided with an exterior annular recess 4a which is so constructed as to provide for the engagement of the prongs 26 of the baffle 25. It will be noted that in this modification the position of the prongs is just opposite to that shown in Fig. 1. The baffle 25 in either case of course may be simply slipped within the opening so as to allow the prongs to spring within the respective grooves 27 and 4a of Figs. 1 and 3, respectively.

In explaining the operation of my device let it be assumed that a supply fixture, as for example, a flushing valve connected by threaded tubing at 2 to the head 1 has been actuated, thus creating the flow of the flushing stream through the throat 4 and into the apertured passage 16a of the baffle 16. Such stream-flow being under relatively high velocity, as previously mentioned, tends to draw the air inwardly from the atmosphere through the aforementioned ports 5a and the annular spaces existing exteriorly and interiorly of the vertical walls 25a of the cylindrical baffle 25 and also between the interior periphery of the baffle ring 22 and the outer periphery of the nozzle member 4b. The stream passing downwardly through the preferably restricted throat 4 continues directly through the port 16a of the primary baffle 16 and thence through the port 13 and past the secondary baffle 14 of the outlet ring 8. The incoming air through the preferably arcuately positioned ports 5a is drawn in from the surrounding atmosphere, and the path of the air taken in is that as indicated by the arrows shown. It is of course apparent that the incoming air because of its frictional contact with the flushing stream emerging from the mouth of the nozzle member 4b causes a certain degree of turbulence and a mixture of water and air, particularly below the baffle 16 and at the point where the stream enters the respective ports 16a and 13. This mixture of air with the water is quite as effective as a corresponding volume of water alone for flushing, thus resulting in a substantial economy in the amount of water ordinarily necessary for such flushing purposes.

Thus, in the event that a vacuum should be created within the inlet pipe or fixture (not shown) which might be traceable to a variety of causes, as for example, by shutting off a valve in the fresh water supply line or else from a relatively heavy consumption of water at a lower level, it is readily apparent that it is absolutely impossible for any reversal of flow to take place through my device or for the liquid level to rise to any noticeable height within the outlet tail-piece 11 under vacuum, due to the generous size of air ports 5a which are always open to atmosphere to provide a full and free inward air flow. Therefore, since the pressure within the device surrounding the throat 4 and the respective auxiliary and primary baffles 25 and 16 is substantially the same as that of the atmosphere, there exists no possibility that a partial vacuum within the inlet pipe entering at 2 might cause a reversal or back-up of flow of the flushing stream. Briefly, the incoming air from the atmosphere instantly and positively prevents even the tendency of a vacuum to form.

Further, as to any splashing or "spitting" into the atmosphere, during the flushing operation it is obvious that the baffle formed by the shoulder 14 of the outlet ring 8 effectively inhibits such tendency of any reverse flow to pass upward

within the inner wall of the tubing 11 and into the body 5, except by a circuitous or broken flow. However, even should the latter flow condition become such that the flushing water reverses 5 sufficiently causing upward flow through the port 13, it is apparent the inwardly sloping rim or wall constituting the baffle 16 and terminating within the limits of the port 16a tends to direct such flow through annular opening 18c thence 10 into the intervening chamber 18d of relatively low pressure. Since the surface 16b of the baffle 16 slopes downwardly toward the port 16a and the peripheral lip 22a of the baffle ring 22 likewise curbs and directs any flow from the annular 15 openings 18a and 18b downward toward the port 16a where the high velocity stream pulls it inwardly, an ejector action is created. In addition, the tendency of "spitting" within the device is further curbed and prevented from escaping into 20 the atmosphere by the cylindrical walls 25a of the auxiliary baffle 25 which tend to prevent this undesirable "spitting" previously referred to. It is obvious, of course, that the passage formed by the cylindrically extending wall 25a and supported by the prongs 26 may be made of sufficient 25 length or form so as to serve as an even more effective restraining means insofar as the tendency of the back stream or droplets to pass into the atmosphere by way of the ports 5a is concerned.

30 Directing attention now to Fig. 4, the outlet ring 8 is of a special construction having an annular depending projection or extension 8b for use under high pressure conditions, as for example, those installations involving what is known to the trade as blow-out bowls. In this class of service because of the higher pressure and velocities which are used, it is essential that even greater precaution than heretofore considered be 35 taken to provide against the possible back-flow of the flushing stream. Therefore, in this connection it has been found desirable to provide for an annular space 8c, which preferably exists between the outside diameter of the aforementioned extension 8b and the interior peripheral surface of the tubing 11. Obviously, the annular extension 8b thus serves as an additional restraining means to prevent the inward radial flow into the port 13 and thence upward into the 40 device. A rough and only conventional cylindrical extension has been shown and it is obvious that its form may be changed to suit the varying conditions of each installation.

45 It is thus apparent that I have devised an effective and simple construction for this service featuring a number of baffles in combination with the advantage of an ejector action and an outlet orifice arrangement which absolutely prevents the possibility of any water from either flowing, 50 creeping or splashing outwardly from within the side walls or through the respective air relieving passages into the atmosphere to thereby create an objectionable and very insanitary condition.

55 I am aware that there have been numerous devices heretofore proposed to meet the condition mentioned. However, none of these prior devices, to my knowledge, has been available which effectively prevents the escape of water into the atmosphere under high pressure and/or high velocity flushing flow conditions.

60 It is further apparent that the construction and detailed means of accomplishing the results above mentioned may vary considerably, and I desire therefore to be limited only to the extent 65 of the claims appended hereto.

I claim:

1. In a vacuum breaker device comprising an inlet and an outlet in substantial axial alignment, a plurality of superposed baffles therewithin, a restricted throat portion extending downwardly from the said inlet, an auxiliary splash baffle supported therefrom, a secondary baffle 5 within the said outlet, a primary baffle therebetween having an annular space peripherally arranged to cooperate with the flow through said throat portion whereby an aspiratory effect over the said baffle is produced, air vents adjacent thereto and means within the said vacuum breaker for supporting said baffles in fixed relation.

2. In a vacuum breaker device comprising an inlet and an outlet, a plurality of annularly positioned baffles within the said device, a restricted orifice portion within the said inlet creating an ejector action past the said baffles, air relieving vents above the said baffles, a spray baffle superposed above said baffles and extending transversely adjacent to said air relieving means, and connecting means within the said device for fixedly supporting the said baffles.

3. In a vacuum breaker device comprising a 25 head having an inlet and a casing having an outlet, a plurality of annularly formed baffles within the said device, a baffle ring therebetween, a primary baffle supported by the said ring, a restricted orifice emanating from within the said 30 head whereby the fluid flow therethrough cooperates with the said baffle ring and the said primary baffle to produce an aspiratory action over the latter, a lower secondary baffle adjacent to the said outlet, air relieving means positioned 35 above said baffles, and means within the said vacuum breaker for fixedly supporting the said baffles.

4. In a vacuum breaker device comprising a 40 head having an inlet and a casing having an outlet, a plurality of baffles in superposed relation, a restricted orifice emanating from within the said head and creating an ejector action 45 therewithin, a baffle ring within the said casing, an upper baffle having a substantially vertical cylindrical wall and supported by the said baffle ring, air relieving means annularly positioned above the said baffles and an annular space between one of said baffles and the interior of said casing cooperating with the ejector action of the 50 said orifice, the said baffle ring being superposed above the said annular space, and means within the said device for fixedly supporting said baffles.

5. In a vacuum breaker device comprising an 55 inlet and an outlet, a plurality of superposed baffles within the said device, an intermediate baffle, a restricted orifice creating an ejector action upon the surfaces of the said intermediate baffle, air relieving means annularly positioned above said baffles, a lower apertured baffle contributing to the said ejector action, and peripherally arranged means within the said device for maintaining the said baffles in fixed position with relation to the said orifice.

6. In a vacuum breaker device comprising an 65 inlet and an outlet, a plurality of superposed baffles within the said device, an intermediate baffle therebetween, the latter having a frustoconical form with a central port therethrough, a restricted throat portion within the said inlet 70 in axial alignment, air relieving means above all of said baffles, the uppermost baffle being so positioned as to provide an annular space between the said baffle and the interior of the said device whereby said air relieving means are pe- 75

ipherally divided, and means within the said device for maintaining each of the said baffles in fixed relation.

7. In a vacuum breaker device comprising an inlet and an outlet, a plurality of superposed baffles in axial alignment within the said device, a restricted throat portion extending downwardly from the said inlet, annularly arranged air venting means above said baffles, one or more of the latter providing for a common flow, creating thereby an auxiliary ejector action cooperating with the said throat portion to carry accumulated backflow from the said baffles, and means within the said device for supporting said baffles.

8. In a vacuum breaker device comprising an inlet and an outlet, a plurality of baffles in substantial axial alignment within the said device, a restricted throat portion emanating from the said inlet, a secondary baffle, a primary baffle superposed above said latter baffle, the said throat in cooperation with the fluid flow therethrough creates an inspiratory action over the surfaces of the said primary baffle, air ports in communication with the atmosphere, connecting means within said device for maintaining the said baffles in fixed relation.

9. In a vacuum breaker device comprising an inlet and an outlet, a plurality of baffles in substantial axial alignment within the said device, a restricted throat portion leading from the said inlet, a secondary baffle within the said outlet, a primary baffle superposed annularly above said latter baffle, air ports in communication with the atmosphere whereby in combination with a flushing flow through said throat portion an inspiratory ejector action is created around said primary baffle, means within said device for maintaining the said baffle in fixed relation.

10. In a vacuum breaker device comprising an inlet and an outlet, a plurality of baffles in substantial axial alignment within the said device, a restricted throat portion emanating from the said inlet and directing a flushing stream in a central passage common to said baffles, a secondary baffle having a lower depending annular extension therefrom, a primary baffle superposed above said latter baffle and having an annular space between said baffle and said device, whereby said stream creates an aspiratory effect over the surfaces of the said baffle, air ports in communication with the atmosphere, means within said device for maintaining the said baffles in fixed relation.

11. In a vacuum breaker device comprising an inlet and an outlet, a plurality of baffles in substantial axial alignment within the said device, a restricted throat portion emanating from the said inlet, a secondary baffle, a primary baffle superposed above said latter baffle, venting means in proximity to said primary baffle, an auxiliary baffle of substantially cylindrical cross-section surrounding said throat portion, a baffle ring cooperating with said primary baffle, whereby backflow drawn over the surfaces of the said

primary baffle is deflected inwardly toward the central portion thereof, and means within said device for maintaining the said baffles in fixed relation.

12. In a vacuum breaker device comprising an inlet and an outlet, a plurality of baffles in substantial axial alignment within the said device, a restricted throat portion emanating from the said inlet, a secondary baffle within the said outlet, a primary baffle superposed above said latter baffle, air ports in communication with the atmosphere, an annular space between the said device and the said baffle, the latter cooperating with the said throat portion whereby flow of the flushing stream through the latter creates an inspiratory ejector action over the said primary baffle, annular means within said device for maintaining the said baffles in fixed relation.

13. In a vacuum breaker device comprising an inlet and a casing having an outlet, a plurality of baffles substantially co-axial within the said device, a restricted throat portion emanating from the said inlet and extending within said baffles, a secondary baffle within said outlet, a primary baffle superposed above said latter baffle, a baffle ring annularly positioned within said casing above the said primary baffle, the latter ring directing backflow over the said primary baffle, air ports in communication with the atmosphere, means within said device for maintaining the said baffles in fixed relation.

14. In a vacuum breaker device comprising an inlet and an outlet, a plurality of baffles in substantial axial alignment within the said device, a restricted throat portion emanating from the said inlet, a secondary baffle within said outlet and provided with an inwardly disposed flange portion forming a passage therethrough, a primary baffle of frustro-conical form and superposed above said latter baffle, a clearance around the periphery of said primary baffle, annular diverting means above said clearance, air ports in communication with the atmosphere and cooperating with said throat portion to create an inspiratory ejector effect over the surfaces of the said primary baffle, connecting means within said device for maintaining the said baffles in fixed relation.

15. In a vacuum breaker device comprising an inlet and a casing having an outlet, a plurality of baffles in substantial axial alignment within the said device, a restricted throat portion leading from the said inlet, a secondary baffle within said outlet, a primary baffle of inverted frustro-conical form superposed above said latter baffle, said primary baffle being positioned to provide for a substantially annular clearance with the interior of the said casing whereby incidental flow therethrough may be diverted to pass over the upper surface of the said baffle, air ports in communication with the atmosphere, and means within said device for maintaining the said baffles in fixed relation.
